HUGO KIEHL, INVENTOR:

BY *Michael Stark & Sons*
ATTORNEYS.

UNITED STATES PATENT OFFICE.

HUGO KIEHL, OF CHICAGO, ILLINOIS.

ELECTRIC INCANDESCENT LAMP.

1,217,775.

Specification of Letters Patent. Patented Feb. 27, 1917.

Application filed April 5, 1916. Serial No. 89,123.

To all whom it may concern:

Be it known that I, HUGO KIEHL, a subject of the German Empire, and a resident of the city of Chicago, in the county of Cook and State of Illinois, have invented a certain new and useful Improvement in Electric Incandescent Lamps; and I do hereby declare that the following description of my said invention, taken in connection with the accompanying sheet of drawing, forms a full, clear, and exact specification, which will enable others skilled in the art to which it appertains to make and use the same.

My invention relates generally to improvements in electric incandescent lamps, and it consists, essentially, in the novel and peculiar combination of parts and details of construction, as hereinafter first fully set forth and described and then pointed out in the claims.

The object of my present invention is the production of an electric incandescent lamp possessing a very high illuminating capacity without materially increasing the cost of manufacture of the same. To attain this result, I construct this lamp in a manner clearly shown in the drawings, in which Figure 1 is an elevation of an electric incandescent lamp, constructed in accordance with my invention. Fig. 2 is a diagrammatic view of the filament of this lamp, illustrating the same in a developed plane. Fig. 3 is a plan on an enlarged scale showing diagrammatically, the course of the filament. Fig. 4 is a plan on an enlarged scale, of a multiplicity of intertwined strands or members of said filament. Fig. 5 is a fragmental view of a modified form of construction of the same.

Like parts are designated by the same characters and symbols of references in all the various figures.

In these drawings A, designates the electric incandescent lamp as a whole. It comprises a glass bulb 12, having the usual metallic male screw member 13, to afford means for attachment of a standard lamp socket, not shown, which male screw member forms one of the electric conductors, and a contact point 14, forming the other element of said electric conductor. Into this bulb leads the current-conducting element 15, downwardly to near the lower end of the bulb, and also a pendant member or post 16, which post carries at its lower end radially projecting arms 17. Near the upper end of said pend-

ant post there are further, radially extending arms 18, all of which said arms are preferably hook-shaped at their free extremities, as clearly shown in Fig. 1. 60

To the aforesaid arms there is hooked the lamp filament, which filament may be of any of the, at present known, electrical conductors. Assuming that the conductor 15 is the positive element of the lead, it turns at the lower end of the bulb, at a point marked *a* upwardly to a point marked by the numeral 2; it then returns downwardly to a point marked *b*, and then again upwardly to a point marked 3. This winding is then repeated to the successive points *c*, 4, *d*, 5, and *e*, from which the lead turns upwardly at 19, and outwardly and out of the bulb in the usual manner. 70

This method of stringing or leading the filament, I have, however, discovered does not afford the maximum of light effect; and to increase the same, which is the object of this invention, I proceed, as follows:

Instead of leading the members 20, 21, 80 Fig. 2, upwardly and downwardly, as described, I intertwine or twist these two strands together, and I do so to the next strands 22 and 23; 24 and 25; 26 and 27, as clearly shown; and actual trials have demonstrated the fact that I have attained an increase in light efficiency of over 50 per cent. I have also experimented with a filament consisting of a multiplicity of intertwined members, as indicated by the reference numeral 40, in Fig. 4, and have found that this method of constructing the filament, and leading the same through the bulb either by the presently practised method, or intertwining the adjacent filament strands, 90 as above described, has resulted in a still greater light-giving capacity of the incandescent lamp. 95

The fragment of a filament shown in Fig. 4, indicates a strand comprising a multiplicity of members intertwined or twisted like a cord or rope; but it is to be understood that this strand is to be trained over the hooks of the supports in the bulb in all respects the same as if the filament were but 100 a single strand.

I now desire to call attention to the fact that the loops *a*, *b*, *c*, *d*, and *e*, and 2, 3, 4, and 5, are quite open, and that the intertwining of the strands between the hooks, 110 commences and ends at some distance from these respective hooks, the result being that

the portions of the filament between the loops and where the intertwining begins, glows only with an intensity due to the electric current passing through these portions while 5 the intertwined portions glow with increased intensity. The intertwining of the strands is an open winding, and is best shown in Fig. 5, the fragility of the filament excluding the possibility of a close winding or 10 intertwining of these strands.

It is, of course, evident that the downwardly pending rod 16, is constructed of a non electricity conducting material which is not affected by the heating conditions of 15 an electric incandescent lamp, such as glass, and that the arms radiating from said pendant rod are constructed of a material or metal not affected by heat to any appreciable extent.

20 Should the manufacture of a continuous filament, as shown in Fig. 2 present difficulties in the intertwining and training, I shall form the filament in sections, as shown in Fig. 5, in which 32 indicates one of said 25 strands, and 33 the other of two adjacent strands. These two strands I shall then unite at their terminals to the next following strands 34, 35, as shown at 36, whereby a continuity of the electric conductor is at 30 attained in an efficient manner.

Having thus fully described my invention I claim as new, and desire to secure to myself by Letters Patent of the United States:—

35 1. In an electric incandescent lamp, filament supports in said lamp, a filament, said filament comprising a series of strands, adjacent strands of said series being in contacting relation to each other at a point remote 40 from said supports.

2. In an electric incandescent lamp, filament supports in said lamp, a filament, said

filament comprising a series of strands, said strands comprising a multiplicity of members, adjacent strands being in contacting 45 relationship to each other at a point remote from said supports.

3. In an electric incandescent lamp, filament supports in said lamp, a filament, said filament comprising a series of strands, adjacent strands of said series being intertwined at a point remote from said supports. 50

4. In an electric incandescent lamp, filament supports in said lamp, a filament, said filament being trained in a zigzag up and down manner over said supports, adjacent members of said filament being in contacting relation to each other at a point remote from 55 said supports.

60 5. In an electric incandescent lamp, filament supports in said lamp, a filament, said filament being comprised of a plurality of strands, said strands being intertwined, said strands being trained in a zigzag manner 65 over said supports, adjacent members of said strands being intertwined at a point remote from said supports.

6. An electric incandescent lamp, including, a transparent bulb, electric current-carrying leads into and out of said bulb, means in said bulb for supporting a filament therein, said means including a post, a series of upper arms and a series of lower arms, said arms being hook-formed at their free ends 70 and in current-carrying connection with said leads, and a filament in said bulb, said filament being trained over said hooks with open loops, adjacent strands of said filament being intertwined, the intertwining beginning at some distance from said hooks. 75

In testimony that I claim the foregoing as my invention, I have hereunto set my hand.

HUGO KIEHL.
